(57) CLAIM

The ornamental design for a fabric urn cover, as shown and described.

DESCRIPTION

FIG. 1 is a front perspective view of a fabric urn cover showing my new design.

FIG. 2 is a front view thereof; the rear view is a mirror image thereof.

FIG. 3 is a right side view thereof; the left side view is a mirror image thereof.

FIG. 4 is a top view thereof; and,

FIG. 5 is a bottom view thereof.

The fabric urn cover has triangular top flaps with inner ends connected by a fastener.
